UNITED STATES PATENT OFFICE.

CHESTER W. DUDLEY, OF BOSTON, MASSACHUSETTS.

CLOTHES-RACK.

1,031,989.

Specification of Letters Patent. Patented July 9, 1912.

Application filed November 9, 1910. Serial No. 591,519.

To all whom it may concern:

Be it known that I, CHESTER W. DUDLEY, of Boston, in the county of Suffolk and Commonwealth of Massachusetts, have invented certain Improvements in Clothes-Racks, of which the following description, in connection with the accompanying drawings, is a specification, like reference characters in the drawings indicating like parts 10 in the several figures.

This invention relates to clothes-racks and more particularly to detachable clothes-racks.

Heretofore it has been customary to provide folding clothes-racks for various purposes, such racks being suitable for attachment to convenient supports, as to the wood-work within a room, and arranged to be folded when not in use. Such folding clothes-racks, however, were intended to be secured by comparatively permanent means to the wood-work, as by screws, and were capable of being readily folded, but were incapable of being readily detached and removed when not in use. Such prior racks, if intended for outdoor use, were not sufficiently braced or formed to be suitable for outdoor use because of the extra strain incident to wind pressure, particularly when the rack was loaded with clothes or the like; and outdoor folding clothes-racks were entirely unsuitable for indoor use, and, so far as I am aware, neither such indoor nor outdoor racks were capable of being readily detached from their supports and removed.

It is an important object of this invention to provide a clothes-rack, suitable for use either within a room or without, which shall be readily detachable and easily attached, and which shall be sufficiently braced or formed to withstand the wind pressure put upon it when in outside use.

In the preferred embodiment of the invention a detachable clothes-rack is provided, suitable for outdoor use, comprising a horizontally arranged frame which is pivotally connected with a bracket or bracing member, and the inner ends of both the horizontal frame and the bracket are adapted to be detachably connected with the exterior wood-work of an ordinary window frame.

Referring to the drawing illustrating the preferred embodiment of the invention: the figure shows, in perspective, the exterior of a building with the usual wooden

window frame, with my detachable clothes-rack attached thereto. The dotted line indicates how the clothes-rack may be folded when not in use, if it is not desired to detach it entirely.

The numeral 1 designates the usual wooden window sill, and 2 and 3 the side frames thereof. Suitable screw eyes 4 and 5 are secured in the window sill 1 and similar screw eyes 7 and 8 are placed in the frames 2 and 3 respectively. The screw eyes 4 and 5 should be spaced apart a suitable distance to fit the spread of the clothes-rack intended to be held, as will be readily understood, and the screw eyes 7 and 8 should similarly be placed at a height appropriate for the length of the bracket or bracing member of the rack.

As herein shown, the clothes-rack comprises a U-shaped frame 10, 11, and 12, preferably formed from a continuous piece of galvanized wire, brass or the like, and a U-shaped brace or bracket member 14, 15, and 16, which may be formed of similar material. The inner ends of frame arms 10 and 12, and of the brace arms 14 and 16 are preferably formed with suitable bends, which may be substantially right-angled in order to engage the sockets of the screw eyes. The rack, being of metal, will provide sufficient resiliency to retain these bent ends in the screw eyes, when they are "sprung" into engagement therewith. The frame arms 10 and 12 are preferably provided with loops as indicated at 17 and 18, through which the portion 15 of the brace member passes, thus forming a strong pivotal connection between the brace and the frame. In order to enable the frame to be folded and allowed to hang downwardly out of the way, when not in use, it may be desirable to form the inner end portions of the frame arms 10 and 12 with offset sections 20 and 21, so that the frame arms can be folded downwardly over the projecting portions of the window sill, as indicated in the dotted lines in the drawing. Such folding is quickly accomplished by simply detaching the brace arms 14 and 16 from their respective screw eyes 8 and 7, and permitting the entire rack to hang by the lower screw eyes 4 and 5. It will be noted that

this construction provides a clothes-rack which can be readily and instantly detached and entirely removed, or may be partially detached and folded downwardly, and yet

which is so formed as to provide a rigid brace and be capable of withstanding all the strain and stress incident to out-of-door use in windy weather. This device is particularly adapted for use in the modern apartment houses, where facilities for drying clothes are very limited and unsatisfactory.

The detachable rack of my invention can be made of appropriate width to fit the standard sizes of windows and of such length as desired. A plurality of cross-bars similar to the arms 11 and 15 may be provided in racks of suitable size, or an ordinary clothes-line may be run from one arm 15 to the other, to increase the clothes-holding capacity of the rack. The location of the pivotal connection between the frame and the bracket member is, of course, dependent upon the style and size of the rack, the important feature being that a bracing construction is thereby obtained to render the clothes-rack safe and suitable for outdoor use.

Having described my invention, what I claim as new and desire to secure by Letters Patent of the United States is:

1. A pair of U-shaped frames, one of

said frames having eyes intermediate the terminals of its side arms, the other frame having its intermediate portion journaled in said eyes, and means for detachably securing the side arms of both frames to the window frame.

2. A detachable clothes rack, comprising a pair of U-shaped members, one of said members being a bracket member adapted to be detachably secured to the sides of a window frame and pivotally connected to the other and horizontal member at a point intermediate its length, said horizontal member having its inner end portions offset, whereby both the horizontal member and the bracket member may be folded downwardly when the bracket member only is detached.

In witness whereof I have hereunto signed my name in the presence of two witnesses at Boston, Massachusetts, this 31st day of October 1910.

CHESTER W. DUDLEY.

Witnesses:

JAMES R. HOPPER,
JOHN H. McCREADY.
